(57) **CLAIM**

The ornamental design for a hair dryer concentrator, as shown and described.

DESCRIPTION

FIG. 1 is a front perspective view of an embodiment of a hair dryer concentrator that can be used with a hair care appliance;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom thereof; and,

FIG. 8 is a front perspective view of the hair dryer concentrator of FIG. 1 shown mated to the hair care appliance.

The broken line shown in all of the drawing figures are for illustrative purposes only and form no part of the claimed design. The dash-dot broken lines represent boundary lines that form no part of the claimed design.
